Inventor,
Joseph H. Staley,
By Joseph A. Minton
Attorney,

UNITED STATES PATENT OFFICE.

JOSEPH H. STALEY, OF COLUMBUS, INDIANA.

GEAR-PULLER.

1,381,142.

Specification of Letters Patent. Patented June 14, 1921.

Application filed July 28, 1920. Serial No. 399,505.

To all whom it may concern:

Be it known that I, JOSEPH H. STALEY, citizen of the United States, residing at Columbus, in the county of Bartholomew 5 and the State of Indiana, have invented new and useful Improvements in Gear-Pullers, of which the following is a specification.

This invention is to assist in the removal 10 of gears or other detachable mechanism on shafts where the fit is close and the parts are not readily accessible, and the object is to avoid prying and hammering usually resorted to often to the injury of the parts 15 to be removed and to the accompanying mechanism as well, and to provide a powerful screw-means with grappling hooks that can be easily applied and that will retain a hold once acquired until intentionally released.

I accomplish the objects of the invention by the mechanism illustrated in the accompanying drawing, in which—

Figure 1 is a perspective view of a shaft 25 with gear wheels thereon under process of removal by the use of my invention which is here shown in operative position. Fig. 2, is a view in side elevation of my invention removed from the work to be done. Fig. 3, 30 is an elevation in the direction of the arrow in Fig. 2, with the jaw-clamp removed, and Fig. 4 is an edge view of the clamp detached from the rest of the device.

Like characters of reference indicate like 35 parts in the several views of the drawing.

Referring to the drawing, the head 5 is slotted at its two ends and provided with transverse holes. Jaw-bars 6, 6, terminate at one end of each with a hook 7, and at 40 the opposite ends they have transverse holes through which hinge-pins or bolts 8, 8, are passed to swingingly retain the jaw-bars the ends of which are respectively inserted in the slots in head 5, in the manner shown 45 in the drawing. The jaw-bars are turned with their hooks toward each other, and are adapted to reach across a gear-wheel or other object to be pulled and engage the opposite sides of the object with the hooks. 50 Then the object is pulled toward the head 5 by suitable means, here shown as a screw-bolt 9, the threaded body of which passes through and engages a threaded hole in the head, and bears against the end of the shaft

on which the object is mounted, or other 55 body-portion from which the object is to be taken.

In order to insure that the jaw-bars will not slip off of the object to be pulled, I provide a clamp-bar 10, having end-hooks 60 11 and 12, respectively, to receive the two jaw-bars. Within the hook 11, is a lug 13, to enter detents 14 in the outer edge of its jaw-bar, and the opposite jaw-bar has corresponding detents 14, in its outer edge to 65 receive the pointed end of a set-screw 15, which screws through a threaded hole in the hook 12. The body-portion 16 of the clamp-bar is bent and bowed outwardly or away from the plane of the screw-bolt 9 so 70 as to afford ample clearance therefor or for such portions of the object being pulled or its support as are frequently encountered. The opposite side of the clamp from the body-portion 16, is purposely left open for 75 the free and expeditious placing and removal of the puller.

The outer end of the screw-bolt 9, may be finished with a hexagonal head for the application of a wrench in turning it as 80 here shown, or it may be provided with any of the usual and suitable means for working the screw in and out.

The operation of my device is fully illustrated in Fig. 1, in which 20 is a shaft from 85 which the gear wheels 21 are being pulled. The jaw-bars engage the gear wheel between them; they are retained there by the clamp-bar 10, and the wheels are being pulled by turning screw-bolt 9, the inner 90 end of which is against the end of shaft 20.

Having thus fully described my invention, what I claim as new and wish to secure by Letters Patent of the United States, is—

1. In a device for the purposes specified, a head, a pair of jaw-bars pivoted to the ends of the head, said jaw-bars having inturned end hooks, a screw-bolt passing through a threaded hole in the head intermediate of the jaw-bars, and a clamp-bar having end hooks in which the respective jaw-bars are received and a set-screw terminating outside of the clamp-bar and passing through one of the hooks into contact with a jaw-bar to draw the jaw-bars together against the work.
2. In a puller, a head, a pair of jaw-bars

pivoted to the ends of the head, said jaw-bars having inturned end hooks, a screw-bolt passing through a threaded hole in the head intermediate of the jaw-bars, and a clamp-bar open on one side and outwardly bowed on the other having end hooks to receive the respective jaw-bars, and a set-

screw passing through one of the hooks into contact with a jaw-bar to draw the jaw-bars together against the work.

10

Signed at Columbus, Indiana, this the 24th day of July, 1920.

JOSEPH H. STALEY.
